UNITED STATES PATENT OFFICE.

JOHN D. PUFF, OF EAST ST. LOUIS, ILLINOIS.

BARREL-HOOP.

1,177,723.

Specification of Letters Patent.

Patented Apr. 4, 1916.

Application filed February 14, 1914. Serial No. 818,660.

To all whom it may concern:

Be it known that I, JOHN D. PUFF, a citizen of the United States, and resident of East St. Louis, Illinois, have invented 5 certain new and useful Improvements in Barrel-Hoops, of which the following is a specification.

This invention relates to improvements in barrel hoops, and has for its object a 10 metallic band provided with a crimped or bent-over edge and a projecting hollow stiffening rib whereby the band is given rigidity and strength.

A further object of my invention is to 15 construct a hoop to be used in conjunction with a barrel head fastening device, wherein rods are carried by the head and project through the sides of the barrel, the projecting ends being housed in a loop formed in 20 the hoop. The particular fastening means being disclosed in an application for patent filed by R. H. Puff in the United States Patent Office, Sept. 28, 1912, Serial No. 722,982, Patent No. 1,148,622.

25 A further object of my invention is to construct a hoop of sheet metal having its one edge crimped or turned-over and a channel or loop formed in the material and extending throughout its length, which acts 30 as a stiffening rib as well as a housing for projecting rods by which the barrel head is secured in position, and to retain the hoop in position on the barrel by indenting the hoop, forming inwardly projecting burs.

35 Figure 1, is a side elevation of a barrel showing my improved hoops. Fig. 2, is a vertical sectional view of a portion of the barrel, its head and a hoop in position and the fastening pin. Fig. 3, is a detail sectional perspective view of the hoop with a 40 part broken away.

Referring to the drawings in detail, 4 indicates the barrel, 5 the barrel head, and 6 a pin extending through the head, its end projecting through an aperture 7, formed in the barrel stave, 8 indicates my improved hoop consisting of a strip of non-corrosive sheet metal, its upper edge 9 crimped or over-turned forming a bead 10. In the body of 45 the strip is formed a loop or hollow channel 11, which extends throughout the length 50 of the hoop and is of such size as to accommodate the insertion of the rods 6. These hoops or bands are made of sufficient width to properly support the upper ends of the 55 barrel staves providing a wide contact surface and by the forming of the loop or hollow channel 11, it dispenses with the necessity of boring holes into the wooden hoops commonly used so that the projecting ends 60 of the rods 6 can be inserted. With a hoop of this construction the same is readily applied over the barrel, and the rods can be readily inserted without necessitating the proper adjusting of the hoop to bring the 65 channel in proper alignment with the apertures 7 formed in the barrel stave so that the rods can be inserted. The intermediate hoops or those located on the barrel body between the two end hoops are similarly constructed, but made narrower than those on the ends. These intermediate hoops have a crimped end 12, and a reinforced rib 13. The rib in this instance may be either round, 70 square, or V-shaped as found desirable and 75 most convenient. And by means of the stiffening rib the hoop is given rigidity and strength, the same as if a wire were inserted in the loop. When the hoops are placed in position on the barrel, the flat portion is 80 indented at intervals with a proper instrument providing a V-shaped cut 14, forming a tongue or bur 15, which is forced into the stave acting as a fastening device. A hoop of this character is light, and exceedingly 85 strong, and withstands a greater pressure than the present wooden hoops which are now commonly used. The heads are made in halves and the rods extend only through 90 each of these halves. The rods are inserted 95 in the holes in the staves and the center portion of the head is pressed down. My device operates in connection with the device of Robert H. Puff, barrel head fastenings. Filed Sept. 28th, 1912, Ser. No. 722,982, and allowed Dec. 30th, 1914, Patent No. 1,148,622.

Having fully described my invention what I claim is:—

A barrel hoop consisting of a single strip of material and arranged to fit around the 100 outer periphery of a barrel, a curved bead forming the upper edge of said hoop, a hol-

low loop formed in the body of the hoop and extending its entire length in combination with a barrel head having rods extending therethrough which loop acts as a protector for projecting ends of rods extending through one of the barrel staves, substantially as specified.

Copies of this patent may be obtained for five cents each, by addressing the "Commissioner of Patents, Washington, D. C."

In testimony whereof, I have signed my name to this specification, in presence of two subscribing witnesses.

JOHN D. PUFF.
